US0D1023296S

(12) **United States Design Patent** (10) **Patent No.:** **US D1,023,296 S**
(45) **Date of Patent:** **** Apr. 16, 2024**

(54) **CASSETTE**

(71) Applicant: **KPR U.S., LLC**, Mansfield, MA (US)

(72) Inventors: **James M. Harr**, Wentzville, MO (US);
Joel D. Wiesner, O'Fallon, MO (US);
Kenneth M. Breitweiser, Brighton, IL (US)

(73) Assignee: **KPR U.S., LLC**, Mansfield, MA (US)

(**) Term: **15 Years**

(21) Appl. No.: **29/870,470**

(22) Filed: **Jan. 27, 2023**

Related U.S. Application Data

(60) Continuation of application No. 29/703,471, filed on Aug. 27, 2019, which is a division of application No. 29/563,231, filed on May 3, 2016, now Pat. No. Des. 860,440, which is a division of application No. 29/452,920, filed on Apr. 23, 2013, now Pat. No. Des. 762,850.

(57) **CLAIM**

The ornamental design for a cassette, as shown and described.

DESCRIPTION

FIG. 1 is a front perspective view showing our new design; FIG. 2 is a front view of the design shown in FIG. 1; FIG. 3 is right side view of the design shown in FIG. 1; FIG. 4 is a left side view of the design shown in FIG. 1; FIG. 5 is a top view of the design shown in FIG. 1; and, FIG. 6 is a bottom of the design shown in FIG. 1.

The rear of the cassette forms no part of the claimed design. The broken lines shown in the figures are included for the purpose of illustrating portions of the cassette and form no part of the claimed design.

1 Claim, 5 Drawing Sheets
